HOLDER FOR CIGARETTES AND THE LIKE

Bernard F. Conley, South Chicago, Ill.

Application January 8, 1947, Serial No. 720,781

2 Claims. (Cl. 131—174)

1

This invention relates to holders for cigarettes and the like, and more particularly to such holders adapted to promote safety and cleanliness.

One of the objects of my invention is to provide a holder for cigarettes and the like which embodies a light weight and relatively rigid perforated enclosure for the cigarette, which enclosure is constructed to present a relatively cool outer surface in use and the perforations of which are adapted to retain live sparks within the enclosure.

It is another object of the invention to provide a holder for cigarettes and the like which includes a perforated enclosure for the cigarette, so constructed and arranged that it is adapted to production by molding of a material, such as plastic.

Other objects and advantages of the invention will be apparent from the following description and the accompanying drawings in which similar characters of reference indicate similar parts throughout the several views.

In the one sheet of drawings:

Fig. 1 is an exploded view in side elevation depicting a preferred embodiment of my invention;

Figs. 2 and 3 are end elevational views drawn to a somewhat larger scale than that utilized in Fig. 1 and indicating the structure when viewed substantially as indicated by the lines 2—2 and 3—3, respectively, in Fig. 1;

Fig. 4 is a fragmentary side sectional view wherein the section is taken substantially as indicated by a line 4—4 in Fig. 1 and the accompanying arrows; and

Fig. 5 is a sectional view wherein the section is taken substantially on a line 5—5 of Fig. 4 and viewed in the direction indicated by the accompanying arrows.

In the exemplary embodiment of my invention which is depicted in the accompanying drawings for illustrative purposes, a stem 10 of relatively conventional construction has a mouthpiece 12 at one end and a cigarette-receiving and holding counterbore 13 in the other end with a longitudinal smoke passage 14 extending therethrough. As illustrated by dot and dash lines in Figs. 1 and 4, a cigarette or the like 15 is inserted in the counterbore 13 and supported by the stem in the usual manner with the cigarette projecting axially from the end of the stem.

For use with this relatively conventional type of holder for cigarettes and the like, I have provided an elongated and perforated cover 16 adapted to be carried by the cigarette-holding end of the stem so as to effectively enclose the

normally projecting portion of the cigarette or the like as it burns. The closure not only prevents contact with the ignited end of the cigarette, but promotes safety and cleanliness by retaining sparks and ashes therein while the cigarette is being smoked.

To facilitate manufacturing at low cost, and to provide a structure for the cover which is light in weight as well as durable and effective, I have designed and adapted the same for production by molding of a light weight thermoplastic material. Generally, the cover 16 is cylindrical in shape having an open end 17 for receiving a cigarette such as 15 and the end of the stem 10, and, by preference, tapers inwardly toward a closed end 18. A wall 19, which comprises the cover in my disclosed structure, is desirably provided on its inner surface with a plurality of circumferentially spaced and longitudinally extending ribs 20 which project inwardly in a radial direction to define a cigarette-receiving chamber 21 and longitudinal channels 22. The dimensions of the chamber within the peripheral surfaces of the ribs are such that a cigarette or the like which is supported by the stem will be held within the chamber in spaced relationship to the inner peripheral surfaces of the ribs when the end of the holder is mounted snugly against tapered end surfaces 23 of the ribs at the open end of the cover.

Along a major portion of its outer surface the cover 16 has a series of axially spaced circumferential channels 24, which channels are separated by a series of intervening circumferential ribs 25. The depths of the respective internal and external channels 22 and 24, which channels are transversely disposed relative to one another, are so related to the thickness of the wall 19 that they intersect to provide a multiplicity of perforations 26 in the wall. The widths of the intersecting channels are such that the perforations readily permit the flow of air therethrough, but do not allow ashes, and particularly live sparks, to pass therethrough. It is also desirable that the thickness of the wall, and, consequently, the combined radial thicknesses of the ribs, shall be such that the outer surface of the cover does not become sufficiently hot to burn the user or an article upon which the holder may be placed.

In order to adapt the structure and arrangement of my holder to production by molding processes, although it may be readily made by other methods, I have arranged the respective ribs and channels so that the dies may be readily withdrawn therefrom and so that perforations

are formed by the same dies and in the same operation as the molding of the holder. That is, the core portions of the die which forms the interior of the cover may be withdrawn from the open end 17. This is true whether the longitudinal ribs 20 extend to the extreme open end of the cover or whether they are terminated internally of the cover so as to leave a larger circular opening for the reception and support of the cover by the stem. The mold for the exterior surface, including the circumferential ribs 25 and their intervening channels 24, may be divided and thus removed radially. The dies interfit to provide the intersections of the channels so that the perforations are formed in the single molding operation.

It is readily understandable that the ribs and dies might have different sectional shapes and might be disposed at different angles relative to one another to provide some different pattern or appearance without departing from the illustrated structural advantages. It is also considered to be clearly illustrated by the foregoing description and reference to the drawings that I have provided a cigarette holder adapted to inexpensive and rapid production from light materials, as well as a holder which promotes safety and avoids some of the annoyances or dangers of smoking.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A holder for cigarettes and the like comprising, in combination, a stem having a mouth-piece at one end and a cigarette-receiving bore at the other end, an elongated hollow cigarette cover adapted to fit onto said other end of the stem and including a wall closed at one end and open at the other end for receiving said stem, said wall having on its inner surface a series of longitudinal ribs spaced apart circumferentially and ex-

tending inwardly in a radial direction to define a cigarette-receiving chamber with a longitudinally channelled interior surface, said ribs being defined by surfaces extending to the open end of the cover, and said wall also having in its exterior surface a series of longitudinally spaced annular channels of a depth such that they intersect the channels of the interior surface to provide a multiplicity of perforations in the wall.

- 5 2. In a holder for cigarettes and the like, a safety cigarette cover adapted to be produced by molding of a thermoplastic material and comprising, in combination, a generally cylindrical and axially elongated wall having an open end and a closed end and being of substantially uniform internal diameter along the major portion of its length and tapered inwardly only near its closed end, the inner surface of said wall being provided with a series of axial ribs spaced circumferentially and extending inwardly in a radial direction to define a cigarette-receiving chamber having a longitudinally channelled inner surface with the channels thereof extending to the open end of the wall, and the outer surface of 20 said wall having therein a plurality of axially spaced circumferential channels of a depth sufficient to intersect the longitudinal channels in the inner surface, thereby providing a multiplicity of perforations in said wall as well as an 25 externally ribbed outer surface.
